UNITED STATES PATENT OFFICE.

SAMUEL G. GILLESPIE, OF CHARLESTON, WEST VIRGINIA.

ANTI-DOOR-SLAMMING DEVICE.

1,191,583.

Specification of Letters Patent. Patented July 18, 1916.

Application filed September 2, 1915. Serial No. 48,663.

To all whom it may concern:

Be it known that I, SAMUEL G. GILLESPIE, a citizen of the United States, residing at Charleston, in the county of Kanawha and 5 State of West Virginia, have invented certain new and useful Improvements in Anti-Door-Slamming Devices, of which the following is a specification.

My invention relates to a combined check 10 and anti-rattler for doors and it aims to provide coöperating parts to be attached to the door and to its frame, essentially comprising a roller adapted to travel on a yielding element.

15 Further, I aim to provide a device of this nature which may be readily stamped from sheet metal with the exception of the roller and its pin, so as to be capable of manufacture at a minimum figure.

20 With the above and additional objects, such as will hereinafter appear, in view, the invention resides in the novel arrangement, combination and construction of the parts of the preferred embodiment herein- 25 after described and illustrated in accompanying drawings, wherein:—

Figure 1 is a fragmentary elevation of a door and its frame having my improvements applied thereto; Fig. 2 is a cross sectional view of the same parts as Fig. 1 on an enlarged scale; Fig. 3 is a perspective view of the roller carrying section and Fig. 4 is a perspective view of the track member for the roller.

35 Referring specifically to the drawings, 1 conventionally represents a door adapted to swing relatively to a frame 2.

My improvements may be applied to the door and frame at any suitable location, for 40 instance, above the usual lock 3 as shown in Fig. 1.

The attachment comprises two sections, one of which is shown in detail in Fig. 3. This section has an attaching plate or tang 45 4 provided with apertures 5, being made of bendable sheet metal and having lugs 6 integral therewith and bent at right angles thereto in order to rigidly mount a pin 7 on which a roller 8 is turnably secured inter- 50 mediate the lugs 6. This section is connected to one face of the door by means of screws or the equivalent 9 which pass through the openings or apertures 5. The door is preferably cut away at 10 to provide

the necessary clearance for the working of 55 the roller 8, and the disposition of flanges 6. If preferred, the face of tang 4, the reverse of that shown as fastened to the door, may be secured directly to the door in order to have the roller 8 outermost. 60

The second section of the attachment is illustrated in detail in Fig. 4 of the drawings. This section comprises an inclined track 11, substantially the same width as the roller 8 from which extends a tang 12 65 provided with apertures 13 through which screws 14 may be passed to secure this latter section to the door frame 2. The track portion 11 is yieldable from the junction of tang 12 therewith and when in position, this 70 section is disposed intermediate one side edge of the door and one side edge of the frame 2, as seen in Fig. 2, thus extending substantially at a right angle to the tang 4. An inturned flange 15 may be provided on 75 track portion 11 and the same together with track portion 11 be accommodated for yielding movement by means of the clearance at 16 in the door frame as shown in Fig. 2.

With the parts assembled as shown in 80 Figs. 1 and 2, as the door 1 is closed, roller 8 rides on the track 11 against its tension forcing the track away from the door. Since this action occurs, the door may be forcibly closed or slammed without the usual 85 noise occurring or injury to the door, since the force of the door is checked by the braking action of the roller on the yieldable inclined trackway 11. In addition, while the door is closed, since the track-way 11 exerts 90 a tension against the roller, the door is held against accidental movement, especially such as would result in rattling. It may be mentioned that flange 15 engages the frame 2 from above and below in order to overcome 95 any successful turning movement of the track section.

Since merely the preferred embodiment has been illustrated and described, it is to be understood that changes in the details 100 of construction may be resorted to within the spirit and scope of the appended claim.

I claim:

In combination with a movable member and a support member, a yieldable cam track 105 element on one of said members, the other of said members having a cut-away portion, the latter member having a tang provided

with inwardly extending ears integral therewith, a pin mounted by said ears, and a roller on said pin disposed in said cut-away portion within the outer face of the tang to engage said yieldable track means to tension the same and check the door and prevent rattling thereof.

In testimony whereof I affix my signature in the presence of two witnesses.

SAMUEL G. GILLESPIE.
